CLAIM

The ornamental design for a fuse holder, as shown and described.

DESCRIPTION

FIG. 1 is a top, left perspective view of a fuse holder according to our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof, the other side being a mirror image thereof;

FIG. 7 is a top, left perspective view of a fuse holder according to a further embodiment of the design shown in FIG. 1;

FIG. 8 is a top plan view thereof;

FIG. 9 is a front elevational view thereof;

FIG. 10 is a rear elevational view thereof;

FIG. 11 is a bottom plan view thereof; and,

FIG. 12 is a right side elevational view thereof, the other side being a mirror image thereof.
